UNITED STATES PATENT OFFICE.

MAURICE SULLIVAN, OF NEW YORK, N. Y.

INSULATION-FORMING MACHINE.

1,203,808.

Specification of Letters Patent. Patented Nov. 7, 1916.

Application filed November 16, 1915. Serial No. 61,756.

To all whom it may concern:

Be it known that I, MAURICE SULLIVAN, a citizen of the United States, and resident of the city of New York, borough of 5 Brooklyn, in the county of Kings and State of New York, have invented a certain new and useful Insulation-Forming Machine, of which the following is a specification.

My invention relates to insulation forming machines and has to deal more particularly with machines for the manufacture of a removable and replaceable type of insulation for flanged pipe joints, flanged fitting joints and the like.

15 The invention has for its general objects to improve and simplify the method of producing a split or sectional type of flange insulation, composed of alternate layers of wire cloth and asbestos or magnesia segment blocks and finishing same with plastic insulating composition so that it will be comparatively simple and inexpensive to produce, thoroughly reliable and efficient in use.

25 Another object of the invention is the production of a portable machine for the production of flange coverings capable of binding, forming and plastering same.

Another object of the invention is the 30 provision of a circular or oblong form of mold fitted with radial and transverse channels at the 4 cardinal points of the same and extending inwardly, and adjoining channels running parallel with same. These 35 channels are for the reception of adjustable partitions and fastening attachments so that partitions can be raised or lowered as required.

Another object of the invention is the 40 provision of adjustable partitions fitted with lugs for fastening purposes and a tapered slit cut in the center of each partition and extending inwardly and adapted to receive a binding twine for binding material on a 45 form.

A further object of the invention is the provision of a forming and finishing trowel attached to the end of a balance lever, an adjustable weight being attached to the 50 other end, said lever balanced on an adjustable fulcrum projecting from the frame of the machine. The adjustable weight regulates the necessary pressure required on the

point of the trowel or former while the plastic composition is being applied, with 55 such objects in view and others which will appear as the description proceeds.

The invention comprises many novel features of construction and arrangement of parts which will be set forth with particularity in the following description and claims appended hereto.

In the accompanying drawings which illustrate certain embodiments of the invention and wherein similar characters of reference indicate corresponding parts in all the views, Figure 1 is an elevational side view showing the machine assembled and a disk form of mold mounted on a shaft with the adjustable partitions in place in same. 70 Fig. 2 is a plan view of the machine showing the tension device and twine leading from same to the central slit in the partitions attached to the disk form of mold, the projecting fulcrum and trowel or former mounted on the same. Fig. 3 is a rear vertical view of the machine assembled. Fig. 4 shows a vertical detail view of radial channel and adjoining channel. Fig. 5 is a detail sectional view of the lug attached to adjustable partition for fastening same. Fig. 6 shows an elevational view of adjustable partitions and tapered slit in the center for reception of the binding twine. Fig. 7 shows a plan and elevational view of a lever trowel 85 and former with weight appended and resting on a fulcrum. Fig. 8 shows a disk form C mounted on a shaft with adjustable partition in place and the interior layer of wire cloth wound on the form C, the ends terminating at the partition and extending on the sides a proper distance outside the partition. Fig. 9 shows a disk form C mounted on a shaft with magnesia segment blocks wound on over the interior wire cloth, the marginal 90 sides of the wire cloth being cut at intervals and bent outwardly and against the sides of a block segment. Fig. 10 shows the disk form C mounted on a shaft with the interior wire cloth and magnesia segment blocks and exterior wire cloth wound on the ends of exterior wire cloth projecting beyond the magnesia segment blocks and cut at intervals and bent inwardly and overlapping the sides of the interior wire cloth and both 105 stapled together. Fig. 11 shows the disk

form C with the interior and exterior wire cloth stapled together and a perspective view of the plastic composition applied.

The extension frame F is attached to the center of table A and extends a proper distance for the support of bearing C. The shaft H is set in said bearing, having a handle o attached to the outer end for operating and a cog wheel g attached to the inner end 10 of the pawl h, and its stand jj, being attached to the table proper, the pawl engaging the cog wheel g as shown in Fig. 2.

The mold C is mounted on the shaft H and placed between collars m. m. and secured rigidly thereto by manipulating nut n, as shown in Figs. 1 and 2 respectively. Inserted in the radial channels J of mold C is the adjustable partition R, as shown in detail in Fig. 6, and in Figs. 1—2 and 3, 20 joining the radial channel J and running parallel with the same is the channel I, in which is inserted the bolt i, which is connected with lug v attached to partition R, by this means the partitions can be adjusted 25 or raised and lowered to depth required.

A tapering slit t, is cut inwardly in the center of partition R for the reception of the binding twine a, which is attached to said slit t, and on form C being rotated the tension on twine a, draws the spring lever M 30 forward, the pawl h and the cog wheel g catching at every degree of a revolution and on form C being stopped revolving the spring lever M moves backward until pawl 35 h catches in cog wheel g, this insuring a uniform tension on the binding twine a, at all stages of the winding.

Projecting from table A is an adjustable fulcrum E, bolted to channels Y. Y. as 40 shown in Fig. 2. Balanced on said fulcrum E is the crossbar X adjusted on the same by collars e. e. Attached to crossbar X is the balance lever L to one end of which is attached a forming and finishing trowel V, 45 and on the other end an adjustable balance weight W, as plainly shown in Figs. 1—2 and 7, by this means the necessary pressure is brought to bear on the point of the trowel when plastic composition is being applied.

50 The method of manufacturing the covering will be described in connection with Figs. 8 to 11 inclusive. The first step in the forming of the covering is having the wire cloth and magnesia segment blocks cut to their proper dimensions. The binding twine a, is drawn through tension device P, and entered into slit t, in partition R and fastened, the mold C being suitably rotated the interior wire cloth c. c. as shown in Fig. 55 8 is wound on said form, the ends terminating at each partition and held firmly on the face of mold C by the tension on the binding twine a, the twine a entering the slit t at every 90 degree revolution of form C and descending to the bottom of the slit t, holds

the material firmly on the form at all stages of the winding process. The magnesia segment blocks d. d. are then laid over the wire cloth c. c. the binding twine a, holding them firmly in place until they surround the form 70 C. The marginal sides of the wire cloth c. c. is then cut at intervals and bent outwardly and against the sides of segment blocks d. d. as shown in Fig. 9. An exterior wire cloth f. f. is then wound on over the magnesia segment blocks d. d. the ends terminating at the partitions as before, the marginal ends or sides of the wire cloth f. f. is then cut at intervals and bent inwardly, overlapping the edges of the interior wire c. c. and projecting inwardly as a support for the sides. Both wires are then fastened by driving staples i. i. through them and into the magnesia segment d. d. as shown in Fig. 10, the binding twine a is then cut and the end fastened. Stove bolts g. g. are then inserted radially through the covering and tightened with nuts at the sides of each partition R. The alternate layers of wire cloth and magnesia segment blocks being wound on the form 90 C and securely bound together the plastic composition is now spread over the top of the covering by hand and the form C being rotated rapidly the forming trowel V spreads the material over the surface of the 95 covering and trowels the plastic material on the face sides and edges of the covering down to a smooth, true and hard finish. When the covering is completed a knife is inserted at the sides of the partitions and the binding twine cut through. Thus the 100 sections of covering are removed from the form.

From the foregoing description taken in connection with the accompanying drawings 105 the advantage of the construction and method of operation will be readily understood by those skilled in the art to which the invention appertains, and while I have described the device which I now consider to be the best embodiment thereof, I desire to have it understood that the device shown is merely illustrative and that such changes may be made when desired as are within the 110 scope of the appended claims.

Having thus described my invention, I claim as new and desire to secure by Letters Patent:

1. The combination in an insulation forming machine, of a disk rotating form of mold, fitted with radial channels extending inwardly from the outer edge of the mold and at right angles to each other, a system of adjustable sliding partitions and their attachments for fastening fitted in said channels, and a tapering slit cut in the center of each partition as fully described and set forth.

2. The combination in an insulation forming machine, of a projecting and adjustable 130

fulcrum, a balance lever resting on the fulcrum, a forming trowel attached to one end of balance lever, and an adjustable balance weight on the other end, all substantially as set forth.

3. An insulation forming machine comprising a disk form of mold mounted on a mandrel or shaft to rotate, said mold fitted with recesses or channels for the reception of two or more adjustable dividing partitions, each partition provided with a tapering slit in center and projecting inwardly to the face of the mold, a balanced lever trowel engaging the face of the mold and regulated by a balance weight, the balance lever resting and supported on a projecting fulcrum which is adjustable all substantially as set forth.
- 15 4. The combination in an insulation form-

ing machine of a disk form of mold mounted on a shaft and fitted with adjustable 20 dividing partitions each partition provided with a tapering slit cut in the center, a balanced lever trowel, and balance weight supported on an adjustable fulcrum and so arranged that the trowel engages the face 25 of the disk form while same is revolving.

In testimony whereof I have signed my name to this specification in the presence of two subscribing witnesses, at Brooklyn, in the county of Kings and State of New York 30 this 13th day of Nov. A. D. 1915.

MAURICE SULLIVAN.
